LAMINATED TURBINE BUCKETS

Dimitrius Gerdan and Stuart Wilder, Jr., Indianapolis, Ind., assignors to General Motors Corporation, Detroit, Mich., a corporation of Delaware

Application June 9, 1952, Serial No. 292,546

5

17 Claims. (Cl. 253—39.15)

2

and 5—5, respectively, in Fig. 1; Fig. 6 is a transverse sectional view, corresponding to the section of Fig. 4, of a modified form of bucket; Fig. 7 is a longitudinal section of a third form of bucket, this section being taken approximately on the mean camber line of the blade; Fig. 8 is a transverse section of the same taken on the plane indicated by the line 8—8 in Fig. 7; and Fig. 9 is a partial longitudinal section of the same taken on the plane indicated by the line 9—9 in Fig. 7.

Referring first to Figs. 1 to 5, the turbine bucket illustrated comprises a blade portion A and a base portion B mounted in a turbine wheel C which may be of conventional type. The wheel C is provided with a conventional multiple dovetail slot 11 extending across the rim of the wheel for mounting each bucket. The faces of the base or root B of the bucket are formed with serrations 12 which engage in the grooves of the slot 11. The blade portion A may be of any suitable form dictated by the requirements of the installation. The blade form illustrated is a typical one in which the cross-section of the blade is generally of airfoil form, both the chord and the thickness of the blade decrease away from the base, and the blade may be twisted, as will be most clearly apparent from Fig. 5. In short, the external configuration of the blade and root may be the same as conventional turbine buckets which may be replaced by the bucket of the invention.

The invention is also applicable to fixed nozzle blades or stator vanes of turbines, compressors, and such, in which case a different configuration of the end or ends of the blade is ordinarily employed for mounting the fluid-directing portion of the element. The fluid-directing faces of the blade extend from the leading edge 13 to the trailing edge 14. The central part of the blade consists of a number of laminae stacked and brazed together to form a unified structure. These laminae are of two types; laminae 16 shown in elevation in Fig. 2 which extend from face to face of the blade portion, the edges of these laminae thus defining elements of the fluid-directing surface of the blade, and laminae 17 shown in section in Fig. 2. These laminae comprise two parts 17a and 17b defining between them a channel 18 extending the length of the element to conduct a cooling medium such as air from the base to the tip of the bucket. All of the laminae 16 and 17 continue from the blade portion into the base portion of the bucket, and their outer edges define elements of the side faces of the base B which are formed with the serrations 12.

It may be noted that the laminations have extension, or in other words, extend in the directions lengthwise of the blade and form face to face of the blade. This condition might also be defined by a statement that the laminae are perpendicular to a line extending generally chordwise of the blade. Specifically, as shown, the laminae are perpendicular to a line parallel to the direction of the serrations 12 of the blade root.

The base also comprises end blocks 19 and 21 which form the ends of the blade root and have mounted between them and have brazed thereto the base of the laminated structure; that is, the portions of laminae 16 and 17 between the end blocks. The base portion B of the bucket is formed to define an air chamber 22 between the ends thereof to which air may be supplied in any convenient manner as by passages 23 extending through the rim of the turbine wheel C. It will be apparent from Fig. 2 that the passages 18 communicate with the chamber 22. The laminae 16 are punched to define a passage 24 extending lengthwise of the root interconnecting the passages 18.

The leading and trailing edge portions of the blade (in advance of and behind the laminated structure) are defined by generally V-shaped sheet metal parts 27 and 28

Our invention relates to fluid-directing elements for turbomachines such as are generally known by the terms "buckets," "blades" and "vanes" and, more particularly, to those which are adapted for use in axial flow compressors or turbines of known type.

The invention has particularly relation to turbines of high temperature types, since one of the primary objects of the invention is to provide a bucket or the like which is particularly adapted for cooling.

It is generally recognized that the principal factor limiting the efficiency and power output of gas turbines is the limited temperature of the motive fluid imposed by the turbine buckets. It has long been realized that adequate provision for cooling turbine buckets could be beneficial either in increasing the temperature limitation of the engine or in permitting reduced use of critical materials, or both. As a result, many proposals for structures adaptable for cooling have been advanced and some have been used to some extent. Despite the long period of awareness of the need for a satisfactory cooled bucket, progress in this respect has not been satisfactory.

The principal objects of our invention are to provide a turbine bucket or the like having superior characteristics so far as cooling is concerned; which is of high strength, and, moreover, one which is readily adapted to simple production techniques.

This result is attained by the use of sheet metal for the major portion, if not all, of the bucket. A particular feature of the invention is the utilization of laminated sheet metal construction for the major part of the bucket, the laminae being so disposed as to provide channels for cooling air. The outer surface of the blade, which is the fluid-directing portion, may be wholly constituted by the edges of the laminae. Alternatively, the portions of the blade adjacent the leading and trailing edges may be defined by folded sheet metal parts or by solid strips of a highly heat-resistant alloy. In any case, the laminated structure provides a strong, stiff, and lightweight core for the blade in addition to defining cooling air passages.

By virtue of the invention, complicated forgings or castings are unnecessary and machining of the blade may be greatly simplified. Thus, the cost of the bucket, the critical material requirements, and the production difficulties of conventional buckets are greatly reduced.

The nature of the invention, the advantages thereof, and the preferred manner in which the objects of the invention are realized will be apparent to those skilled in the art from the succeeding detailed description of the preferred embodiments of the invention and the accompanying drawings, in which Fig. 1 is a longitudinal sectional view of a turbine bucket mounted in a fragmentary portion of a turbine wheel, the section being taken approximately on the mean camber line of the blade; Figs. 2 and 3 are longitudinal sections of the same taken on the planes indicated by the lines 2—2 and 3—3, respectively, in Fig. 1; Figs. 4 and 5 are transverse sections of the same taken on the planes indicated by the lines 4—4

which may be die-formed from sheet metal. These parts fit against the outermost laminae 16 and the upper face of the end blocks 19 and 21, and are brazed or welded thereto. The leading and trailing edge portions thus define air passages 31, 32, also extending the length of the blade portion and being open at the tip of the blade. Air is conducted into these passages by slots 33 and 34 in the blocks 19 and 21 to which air is supplied through the passages 18 and 24.

As will be apparent, air introduced in any suitable way to the passage 23 will flow through this passage into chamber 22, through passages 18, and from passages 18 by cross-flow through passage 24 into passages 33 and 34, from which it flows through passages 31 and 32. As will be seen, the laminated structure brazed together forms a very strong core or rigid central structure within the blade, the laminae 16 extending from face to face being particularly adapted to resist deflection of the blade and to provide extensive heat radiating surface scoured by the air flowing through the passages 18. Since the laminations may be relatively thin, the passages are of small width and highly efficient transfer of heat is accomplished.

Fig. 6 illustrates a modification of the bucket of Fig. 1, which differs therefrom in that the leading and trailing edge portions 37 and 38 of the blade are solid strips of metal. Since this form does not provide as effective cooling of the leading and trailing edge portions of the bucket as the form of Fig. 1, these parts must necessarily be of a more heat resistant material for the same service conditions and, ordinarily, may be cast or forged from any suitable highly heat resistant alloy such as those used for turbine buckets of conventional type. The end blocks 39 and 41 correspond to the end blocks 19 and 21 of Fig. 1 but are not provided with the channels 33 and 34. The parts 37 and 39 may be integral and, likewise, the parts 38 and 41. The central or laminated part of the blade structure is substantially identical with that of Fig. 1 except that the outermost laminations are the divided laminations 17a and 17b to provide a flow of cooling air adjacent the parts 37 and 38.

Referring now to the third embodiment of the invention shown in Figs. 7, 8, and 9, this form is similar in many respects to those previously described, differing notably in the fact that it is entirely of laminated construction. The central part of the blade and root may be identical with that of Fig. 1 but the leading and trailing edge portions of the blade and the ends of the blade root are formed by laminae which extend spanwise from the root and into the blade portion.

Parts similar to those already explained with reference to Figs. 1 to 5 are identified by the same reference characters as those applied to Figs. 1 to 5. Immediately adjacent the foremost and rearmost laminations 17, cooling channels 51 and 50 are defined within the blade as close as practicable to the leading and trailing edge. Laminae such as 52 which extend across the blade in the lower part of the blade is shown but are bifurcated toward the tip, and laminae such as 53 which are closed toward the tip of the blade but bifurcated nearer the base define these passages. In addition, to increase the size of the channel, laminae 54 which are open at both ends and thus are substantially the same as laminae 17 may be provided between the laminae 52 and 53. The foremost and rearmost laminae identified as 56 extend completely across the blade root to seal off the ends of the root and may extend slightly into the blade portion where it fairs into the base.

This form of bucket offers the advantages of a completely laminated construction but is not as well adapted to cooling as the form of Fig. 1, and not as well adapted to resist heat as the form of Fig. 6.

The method of manufacturing parts of the buckets, assembling them, and unifying them by brazing or the like, need not be described in detail since the procedure

may follow that described in our companion case S. N. 292,545 filed June 9, 1952, entitled "Turbine Buckets". Our application S. N. 292,547, filed June 9, 1952 contains subject matter related to that of this application.

Since the laminated structure assembled from sheet metal stampings is rough, it is necessary to grind or otherwise machine the surface to provide the necessary smoothness and accuracy of the airfoil surface. In the form of Figs. 1 and 6 this machining could be limited to the central part of the surface which is the easiest to contour. In any event, the very ample provision for cooling of the bucket and the high strength of the bucket with relation to its weight permit the use of more tractable materials so that the finishing is less difficult than with alloys such as are commonly used for gas turbine buckets.

The advantages of the invention in providing a strong and heat resistant structure with excellent heat transfer characteristics and adaptability to production will be apparent to those skilled in the art. It may be noted that the stepped contour of the inner wall of the bucket where it defines the passages 51 and 50 considerably increases the heat transfer surface over that which would be provided by a smooth surface and, of course, the laminae extending entirely across the bucket provided a high ratio of heat transfer surface to the heat absorbing outer surface of the blade.

In order to explain the principles of the invention, preferred embodiments thereof have been described in detail. It should be understood, however, that this description is not to be regarded as limiting the invention, as many modifications thereof may be devised by skill in the art within the principles and scope of the invention.

We claim:

1. A fluid-directing blade for turbomachines and the like, said blade having fluid-directing faces and comprising a number of physical united laminae extending in the directions lengthwise of the blade and from face to face of the blade, the edges of the laminae constituting elements of the fluid-directing faces of the blade, some of said laminae extending from face to face of the blade and others of said laminae being open through the center of said other laminae to define passages extending longitudinally of the blade, all of said laminae extending beyond one end of said fluid-directing faces to provide means for attaching the blade to a supporting structure, the chord of the blade decreasing from the said one end, the said laminae including laminae adjacent one edge of the blade being open at the said one end and being closed at progressively increasing distances from the other end to define one side of a passage generally parallel to the said edge of the blade.

2. A fluid-directing blade for turbomachines and the like, said blade having fluid-directing faces and comprising a number of physically united laminae each having extension in the directions lengthwise of the blade and from face to face of the blade, the edges of the laminae constituting elements of the fluid directing faces of the blade, some of said laminae, constituting a first set, extending unbroken from face to face of the blade, and others of said laminae, constituting a second set, defining openings through the centers of said other laminae extending lengthwise of the blade from end to end thereof providing passages extending longitudinally of the blade from end to end thereof, the laminae of the two sets alternating chordwise of the blade.

3. A fluid-directing blade as recited in claim 2 in which the said united laminae define the fluid-directing faces only over the central part of the blade chordwise and the said faces include leading edge and trailing edge portions defined by continuous members of substantially greater chordwise extent than a said lamina mounted on the said united laminae.

4. A fluid-directing blade as recited in claim 3 in which the said members are of sheet metal of channel form and

define air conduits within the leading and trailing edges of the blade.

5. A fluid-directing blade as recited in claim 2 in which the said united laminae define the fluid-directing faces only over the central part of the blade chordwise and the said faces include leading edge and trailing edge portions defined by continuous members mounted on the said united laminae, the said continuous members being solid and of substantially greater chordwise extent than a said lamina and being composed of a highly heat-resistant alloy.

6. A fluid-directing blade as recited in claim 2 in which the entire blade is of laminated construction.

7. A fluid-directing blade for turbomachines and the like, said blade having fluid-directing faces and comprising a number of physically united laminae each having extension in the directions lengthwise of the blade and from face to face of the blade, the edges of the laminae constituting elements of the fluid directing faces of the blade, some of said laminae, constituting a first set, extending unbroken from face to face of the blade, and others of said laminae, constituting a second set, defining openings through the centers of said other laminae extending lengthwise of the blade from end to end thereof providing passages extending longitudinally of the blade from end to end thereof, the laminae of the two sets alternating chordwise of the blade, all of said laminae extending beyond one end of said fluid-directing faces and providing a blade root for attaching the blade to a supporting structure.

8. A fluid-directing blade as recited in claim 7 in which the said united laminae define the fluid-directing faces only over the central part of the blade chordwise and said faces include leading edge and trailing edge portions defined by continuous members of substantially greater chordwise extent than a said lamina mounted on the said united laminae.

9. A fluid-directing blade as recited in claim 8 in which the said members are of sheet metal of channel form and define air conduits within the leading and trailing edges of the blade.

10. A fluid-directing blade as recited in claim 7 in which the said united laminae define the fluid-directing faces only over the central part of the blade chordwise and said faces include leading edge and trailing edge portions defined by continuous members mounted on the said united laminae, the said continuous members being solid and of substantially greater chordwise extent than a said lamina and being composed of a highly heat-resistant alloy.

11. A fluid-directing blade as recited in claim 7 in which the entire blade is of laminated construction.

12. A fluid-directing member for turbomachines and the like, said member comprising a blade portion having faces for directing fluid and an adjacent base portion for mounting the member, the member comprising a number of physically united laminae each having extension in the directions lengthwise of the blade portion and from face to face of the blade portion, the edges of the laminae constituting elements of the fluid-directing

faces of the blade portion, some of said laminae extending unbroken from face to face of the blade portion and others of said laminae defining openings through the centers of said other laminae extending lengthwise of the blade portion from end to end thereof constituting passages extending longitudinally of the blade portion from end to end thereof, all of said laminae extending beyond one end of said blade portion into the base portion and constituting at least part of the base portion.

13. A fluid-directing member as recited in claim 12 in which the said united laminae define the fluid-directing faces only over the central part of the blade chordwise and the said faces include leading edge and trailing edge portions defined by continuous members of substantially greater chordwise extent than a said lamina mounted on the said united laminae.

14. A fluid-directing member as recited in claim 13 in which the said members are of sheet metal of channel form and define air conduits within the leading and trailing edges of the blade.

15. A fluid-directing member as recited in claim 12 in which the said united laminae define the fluid-directing faces only over the central part of the blade chordwise and the said faces include leading edge and trailing edge portions defined by continuous members mounted on the said united laminae, the said continuous members being solid and of substantially greater chordwise extent than a said lamina and being composed of a highly heat-resistant alloy.

16. A fluid-directing member as recited in claim 12 in which the entire blade portion is of laminated construction.

17. A fluid directing member for turbomachines and the like, said member comprising a blade portion having faces for directing fluid and an adjacent base portion for mounting the member, the member comprising a number of physically united laminae each having extension in the directions lengthwise of the blade portion and from face to face of the blade portion, the edges of the laminae constituting elements of the fluid-directing faces of the blade portion, some of said laminae extending unbroken from face to face of the blade portion and others of said laminae defining openings through the centers of said other laminae extending lengthwise of the blade portion from end to end thereof constituting passages extending longitudinally of the blade portion from end to end thereof, all of said laminae extending beyond one end of said blade portion into the base portion and constituting at least part of the base portion, the edges of the laminae in the base portion being formed to engage in a supporting structure.
